DENTURE

Ulysses S. Walton, Memphis, Tenn.

Application November 4, 1941, Serial No. 417,830

1 Claim. (Cl. 32—2)

This invention relates to dentures.

An object of this invention is to provide a means for improving the construction of dentures whereby the marginal edges thereof may be reinforced so that the body of the denture may be made out of initially plastic material which may be made of lighter construction than has heretofore been possible.

Another object of this invention is to provide in a denture such as a plate a metallic reinforcing edge which is constructed of dental metal and which may be readily formed to the contour of the plate.

A further object of this invention is to provide a metallic reinforcing edge for a denture and an improved means for retaining the reinforcing edge on the marginal portions of the plate.

A further object of this invention is to provide a moldable metallic reinforcing edge for the marginal portions of a denture including a tie element embedded in the denture for tying adjacent metallic edge portions together to thereby prevent movement of the edge portions and also prevent spreading of the denture.

A further object of this invention is to provide a denture with a reinforcing edge portion which is so constructed that it may be formed in a dental laboratory without additional tools or equipment.

A further object of this invention is to provide an improved method of forming a denture wherein the reinforcing metallic edge may be initially formed or molded from the plaster cast and subsequently combined with the denture while the latter is in a plastic state.

To the foregoing objects and others which may hereinafter appear, the invention consists of the novel construction, combination and arrangement of parts as will be more specifically referred to and illustrated in the accompanying drawing, but it is to be understood that changes, variations and modifications may be resorted to which fall within the scope of the invention as claimed.

In the drawing:

Figure 1 is a detail top plan of a denture embodying my invention.

Figure 2 is a detail side elevation partly broken away and in section of the denture.

Figure 3 is a sectional view taken on the line 3—3 of Figure 1, and

Figure 4 is a fragmentary sectional view taken on the line 4—4 of Figure 2.

Referring to the drawing the numeral 10 designates generally a denture which in the present

instance is in the form of an lower plate having a body generally designated as 11 in which teeth 12 are embedded. The body 11 is herein shown as a lower plate, but it will be understood that the hereinafter described invention may be used with an upper plate or denture or a fragmentary plate or denture.

The body 11 is substantially U-shaped in elevation and is also U-shaped in transverse section. The body 11 includes an outer longitudinally and transversely arcuate wall 13, an inner longitudinally and transversely arcuate wall 14 and a bottom wall or bight 15. The body 11 is preferably constructed out of initially plastic material which may be either a rubber compound or other suitable phenol resin composition which may be molded or cast in the desired configuration to properly fit the jaw of the individual.

In order to provide a means whereby the outer and inner walls 13 and 14 respectively of the denture may be formed relatively thin so as to provide for a substantially light weight plate or denture, I have provided a metallic reinforcing rim or edge member generally designated as 16. The edge member 16 is preferably formed out of dental metal which may be suitably molded or cast or otherwise shaped to conform closely to the configuration of the body 11. The reinforcing member 16 includes an outer reinforcing member 17 of substantially U-shape in plan which is connected to an inner U-shaped reinforcing member 18 by means of a pair of arcuate connecting members 19 so as to thereby form a continuous metal rim or reinforcing member about the marginal edge portions of the body 11. The outer reinforcing member 17 at substantially the center or bight of the denture is formed with a substantially V-shaped forward portion 20 which is adapted to conform to the configuration of the outer wall 13 at the forward end or side of the body 11.

In order to provide a means whereby the reinforcing member 16 may be firmly held on the marginal portions of the body 11, I have provided a plurality of spaced apart arcuate anchoring members 21. The anchoring members 21 are formed of metal which is preferably of the same make as the metal forming the reinforcing members 17, 18, and 19. The anchoring members 21 are constructed in the form of open loops which have their free ends 22 connected with or formed integral with the lower sides of the reinforcing members 17 and 18. The anchoring members 21 are substantially thinner than the thickness of

the reinforcing members 17 and 18, so that these anchoring members 21 will be entirely embedded within the material forming the outer and inner walls of the body 11 as shown more clearly in Figure 4.

In practice the reinforcing member 16 is preferably formed prior to the insertion of the plastic material within the plastic or plaster mold, and the anchoring members 21 are secured to the under or lower edges of the reinforcing members 17 and 18. After the general configuration of the reinforcing members 17 and 18 has been determined the anchoring members 21 may be secured to the reinforcing members 17 and 18 so as to provide a substantially integral structure. A combined connecting and reinforcing member 23 is connected at one end to the bight 24 of the inner U-shaped reinforcing member 18 and is connected at the other end thereof to the V-shaped member 20 formed at the bight of the reinforcing member 17. The combined connecting and reinforcing member 23 is adapted to be substantially entirely embedded within the bight of the body 11, and the combined connecting and reinforcing member 23 is of longitudinally arcuate configuration as shown in Figure 3, and conforms closely to the configuration of the body 11 at the inner side thereof. The combined connecting and reinforcing member 23 provides a means whereby the reinforcing members 17 and 18 are held against movement relative to the edges of the outer and inner walls 13 and 14 respectively and also provides a means whereby the outer and inner walls 13 and 14 are braced against spreading or contracting.

The reinforcing member hereinbefore described is of such a character and construction that it may be easily and quickly formed in the dental laboratory without any additional tools and with the equipment and material now available in the laboratory. Furthermore, by forming the reinforcing member 16 out of dental metal or the like the reinforcing member 17 can be accurately formed to the exact configuration of the denture. Also by providing for the anchoring of the reinforcing member 16 with respect to the plastic denture body 11 the reinforcing member will be firmly held against movement relative to the denture body, in addition to being capable of being accurately shaped to conform to the configuration of the denture body 11 about the marginal edges of the latter.

The reinforcing member 11 may be made out of gold, silver, alloy, or other dental material, forming a metallic rim or marginal edge portion which will prevent cracking of the walls forming the denture 11. In this manner the denture body 11 may be made out of either rigid or partly rigid material which may have a degree of resiliency, and the reinforcing material will constantly maintain the denture body 11 in the desired configuration.

What I claim is:

A denture comprising a tray-like body formed of initially plastic material, a moldable metallic reinforcing member molded around the marginal edges of said body, and a plurality of anchoring loops fixed to said member and embedded in said body.
